Primary Examiner — Andrew T Nemeth

(57) **CLAIM**

The ornamental design for a pet waste rake and bin set, as shown and described.

DESCRIPTION

FIG. 1 is a top perspective view of a pet waste rake and bin set, showing my new design;

FIG. 2 is a bottom perspective view thereof;

FIG. 3 is another perspective view showing the pet waste rake and bin set in a state of use;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the pet waste rake and bin set, which form no part of the claimed design.

1 Claim, 9 Drawing Sheets
